UNITED STATES PATENT OFFICE.

GEORGE ALBERT BROWNE, OF TACOMA, WASHINGTON.

INDICATOR.

SPECIFICATION forming part of Letters Patent No. 763,956, dated July 5, 1904.

Application filed November 26, 1902. Serial No. 132,925. (No model.)

To all whom it may concern:

Be it known that I, GEORGE ALBERT BROWNE, a citizen of the United States, residing at Tacoma, in the county of Pierce and State of Washington, have invented certain new and useful Improvements in Indicators; and I do hereby declare the following to be a full, clear, and exact description of the invention, such as will enable others skilled in the art to which it appertains to make and use the same.

The present invention relates to improvements in indicators or registers for showing the temperature of crushed-rock rolls; and the object in view is the provision of means for accomplishing such indication through the expansion and contraction of the rolls.

The invention consists of a rack connection with the journal of a roll and gearing connected with said rack for rotating an indicating device.

It also consists in certain other novel constructions, combinations, and arrangements of parts, as will be hereinafter fully described and claimed.

In the accompanying drawings, Figure 1 represents a view in side elevation of a dial and indicator-needle with the operating parts thereof inclosed in a suitable housing. Fig. 2 represents a section taken on the plane of line 2 2 of Fig. 1. Fig. 3 represents a section taken on the plane of line 3 3 of Fig. 1 looking in the direction of the arrow, parts being broken away for disclosing the interior structure.

Referring to the drawings by numerals, 1 indicates a journal mounted in a thrust-bearing of any suitable type and connected with a roll designed for heating crushed rock, into the end of which journal is inserted, preferably threaded, an arm 2, carrying at its free end a cylindrical rack-bar 3, said arm entering any suitable housing 4 and retaining the rack-bar within said housing. Extending from the housing 4 is a tube 5, carrying a casing 6. Within the housing 4 is journaled a shaft 7, which extends longitudinally through tube 5 into the casing 6 and has fixed at its lower end, or that end within the housing 4, a gear-wheel 8, meshing with the rack-bar 3, the teeth of the rack-bar being parallel and

annular, so that the arm 2 and rack-bar 3 may be free to rotate without moving gear 8, but said gear will be rotated upon longitudinal movement of said rack-bar. The upper end of shaft 7, or the end extending into the casing 6, carries a fixed and preferably beveled gear 9, meshing with a gear 10, carried by a shaft 11, journaled centrally of the casing 6 in a spider 12 and carrying at its lower end an indicating-needle 13, moving above any suitable dial 14.

In operation the roll (not shown, but supported by the journal 1) is heated and expands longitudinally, moving said journal with its arm 2 and rack 3, and thereby rotating gear 8, shaft 7, and gears 9 and 10. Thus the shaft 11 and needle 13 will be rotated by the longitudinal movement of the journal 1, so as to be brought about the face of the dial 14 to a distance proportional to the expansion of the said roll, whereby the degrees of heat within the roll may be indicated. It is not absolutely necessary that the dial 14 should be employed, a single mark of indication being sufficient when placed at the proper point relative to the circle or arc described by the point of the needle 13, the object being the registration of the heat of roll supported by journal 1, such heat being indicated by the needle of pointer 13.

By reference to the drawings it will be observed that the housing 4 may be provided with any suitable support or supports—as, for instance, laterally-projecting flanges—such as are illustrated, said flanges being adapted to receive securing means for attaching said housing at any desired point. It will further be seen that the arm 2 is a solid cylindrical smooth bar projecting into the housing and surrounded by a sleeve connected by bolts or otherwise to said housing, constituting a packing-gland, said sleeve serving to prevent lateral play of the arm and rack carried thereby.

Having thus fully described my invention, what I claim as new, and desire to secure by Letters Patent, is—

1. In a device of the class described, the combination with a rotating journal, of a smooth cylindrical arm carried by the end thereof, a housing spaced from said journal and inclosing one end of said arm, a gear within said

housing, an annular rack-bar carried by said arm and meshing with the teeth of said gear and inclosed by said housing, guiding means carried by said housing and surrounding said arm for limiting the same against lateral play, and indicating means actuated by said gear.

2. In a device of the class described, the combination with a journal, of an arm extending from the end thereof, a housing inclosing the free end of said arm, a packing-gland surrounding said arm and forming a bearing

therefor, limiting the same against lateral play, a cylindrical rack-bar extending from the free end of said arm into said housing, a gear engaged by said rack-bar, and indicating means actuated by said gear.

In testimony whereof I hereunto affix my signature in presence of two witnesses.

GEORGE ALBERT BROWNE.
